UNITED STATES PATENT OFFICE.

ADOLPH E. SCHREIBER, OF BROOKLYN, NEW YORK.

ELECTRO-MAGNETIC ENGINE.

SPECIFICATION forming part of Letters Patent No. 269,331, dated December 19, 1882.

Application filed May 1, 1882. (No model.)

To all whom it may concern:

Be it known that I, ADOLPH E. SCHREIBER, of the city of Brooklyn, in the county of Kings and State of New York, have invented a new and useful Improvement in Electro-Magnetic Engines, of which the following is a specification.

The object of the present invention is two-fold: first, to give a greater range of motion to the lever and rod which connects the moving armatures to the balance-wheel or other part to which motion is transmitted, whereby a longer crank, with its consequent advantage, can be used upon such wheel; and, second, to effect a saving of magnetic force by arranging the poles of the magnets in different planes and shaping the faces of the armatures to conform substantially to the different planes of such poles, whereby the armatures, as they approach the poles, will be within a stronger magnetic field during a greater time or distance than would be practicable were the poles of the separate magnets in the same plane with each other and the faces of the armatures not shaped to conform to them.

The first of the above-named objects is carried into practice by attaching a series of armatures directly to a rock-frame, so that they will partake of the motion of such frame—that is, swing from a common center—and will co-operate with a series of magnets arranged upon a lower plane, substantially as hereinafter more fully described and claimed.

The second object above named can be conveniently effected by placing one of the arms of each magnet at an angle or incline with its other arm and shaping the faces of the armatures so as to be substantially parallel with the different planes passing over the poles of the magnets, as hereinafter more fully explained.

The invention is illustrated in the accompanying drawings, (three sheets,) in which Figure 1 is a plan or top view of an electro-magnetic engine embodying the improvements. Fig. 2 is a longitudinal section of the same through the line $x-x$ of Fig. 1, certain parts being shown in elevation. Fig. 3 is an end elevation of the same; and Fig. 4 is a view in elevation of one of the sides of the rock-frame, showing the series of notches or slots in which the arms of the armatures rest.

In the drawings, A represents the frame of the machine or engine, which is of wood, iron, or other suitable material.

B are cross-bars, upon each of which is mounted a series of magnets, one series being designated by C and the other by C'. These magnets, as shown in the drawings, are horse-shoe in shape, having one arm, a , of each vertical and the other arm, b , inclined toward the arm a , so that the same plane surface would not rest upon and cover the two poles of any one of the magnets, and they are preferably secured to plates or straps of iron b' , which in turn are secured to the cross-bars B and electrically insulated from them.

D is a rock-shaft journaled on the points of screws c and c' , which pass through the standards a' in the frame.

E is a rectangular frame, rigidly secured to the shaft D and arranged to rock with it, two of its opposite sides being designated by e and e' .

F and F' are two series of armatures, corresponding respectively with the series of magnets C and C', one series arranged upon each side of the rock-shaft D and frame E, each armature being provided with an arm, d or d' , which is loosely connected to the shaft D. In each of the sides e and e' of the frame E are a series of slots or notches, f and f' , equal in number to the arms d and d' , and regularly increasing or decreasing in depth throughout the series. The arms d rest in the notches f and the arms d' in the notches f' , and by reason of the varying depth of these notches in the sides of the frame the armatures of each of the series will be raised in succession one above the other—that is, in succession by higher planes—as long as the arms d and d' rest upon the bottoms of their respective notches. The distance at which the armatures should rise one above the other will depend largely upon the power of the magnets, as the vertical distance between them should be such that each armature will be brought within the strong magnetic field of its magnets by the action of the preceding magnets and armatures of the series.

In the machine from which the drawings were made the armatures stand each about one inch higher or lower than those next adjacent of the series.

One or more magnets may be arranged to

operate upon each armature. In the drawings two magnets are employed for each armature, so connected with each other and with the commutator that they are magnetized at the 5 same instant, and in this respect may be considered as a single magnet, though in power a decided advantage may be found in increasing the number of coils.

When the arms *b* of the magnets are placed 10 at an incline or angle with the vertical arms *a*, as shown in Fig. 2 of the drawings, and the faces of the armatures are brought into substantially the shape or configuration shown in said Fig. 2—that is, the outer half of the armature made to conform nearly to a plane at 15 right angles to the axis of the inclined arm of the magnet—an advantage is gained as compared with the operation of magnets with their poles in the same horizontal plane upon 20 a plain or unbent armature. This results from the circumstance that although the armature strikes both of the poles simultaneously, yet in its descent, in swinging from the central shaft, *D*, it is nearer the pole of the arm *b* than 25 to that of the arm *a*, and is consequently more fully within the magnetic field than if the pole of the arm *b* were in the same horizontal plane with the pole of the arm *a*.

G is a lever or link, made fast preferably to 30 one side of the frame *E*, so that it is rocked with the frame and the shaft *D*, and it is connected with the pitman or connecting-rod *H* by the usual pivoted joint, the pitman being in turn attached to the crank *I* on the shaft *J* 35 of the wheel *K*. The shaft *J* is journaled at *g* in the frame of the machine.

L M is a commutator, consisting of the stationary disk *L*, loose upon the shaft *J* and insulated therefrom, and the revolving standard 40 *M*, fast to the shaft *J*, and provided with electric conducting points or rollers arranged to pass over the periphery of the disk *L*, which is divided into as many conducting-spaces, insulated from each other, as there are sets of 45 magnets in the series to be placed successively in the electric circuit. The commutator may, however, be of any construction and operation which will fulfill the conditions required—namely, to place the several magnets or sets 50 of magnets within and out of the circuit in regular succession.

The machine is worked by a galvanic battery, one pole of the battery being conveniently connected to the screw *c'* by a wire, *w*, and the 55 commutator-standard *M* being electrically connected to the screw *c'* through the shaft *D*, link *G*, connecting-rod *H*, and shaft *J*. The opposite pole of the battery is connected by the wire *w'* and its branches to each of the sets 60 of magnets, and each of them are connected by separate conductors to the separate parts of the disk *L* which are insulated from each other, but are brought successively in electrical connection with the wire *w*, by which arrangement the sets of magnets are successively magnetized and demagnetized.

The operation of this machine is briefly de-

scribed as follows: The magnets of the series *C*, for instance, are so connected with the commutator that the first of the series, having its 70 armature nearest its poles, is first brought into circuit and magnetized. The armature is brought down upon the poles of the magnets through their attraction, the frame *E* being rocked in that direction upon its shaft *D*. As 75 all the armatures *F* are attached to the frame *E* they will rock with it so long as they rest upon the bottoms of their notches *f*, and as the first armature of the series descends upon its magnets all the armatures will descend 80 through an equal distance, and the second of the series will be brought within the full magnetic field of its magnets. The first magnets of the series are then demagnetized, the second set magnetized and its armature drawn 85 down upon the poles, while the remaining armatures descend toward but not upon the magnets. This operation is continued till all the armatures *F* have been brought down upon the magnets *C*. The armatures *F'*, upon the 90 opposite side of the frame *E*, have in the meantime been raised by the rock of the frame to their full height, and now the magnets *C'* are successively magnetized, the armatures *F'* descending upon their corresponding magnets 95 and the frame *E* rocked backward. By the descent of the armatures *F* and the armatures *F'* alternately the frame *E* is rocked up and down upon the shaft *D* and the power is transmitted to the wheel *K* through the crank *I*, 100 pitman *H*, and link *G*.

It is observed that when four armatures in each series are employed, arranged so that the highest will stand four inches above the poles of its magnets, each armature will be 105 brought within one inch of the poles of its magnets before such magnets are magnetized, and the full magnetic force will be exerted upon each armature when within near proximity to its poles; also, that the range of the rock of 110 the frame *E* will be equal to the distance at which the highest armature stands above the poles of its magnets. After the first armatures of the series have descended upon the magnets the further rocking of the frame in the same 115 direction is not prevented, for the reason that the arms *d* and *d'* are loosely connected to the shaft *D* and to the sides *e* and *e'* of the frame. As the armatures are lifted from their magnets the one which descended last will be lifted 120 first, as it rests upon the bottom of its slot in the side of the frame, while by the continued downward rock of the frame after the preceding armatures have been stopped by contact with the magnets, their slots having passed at 125 varying distances below the plane of the arms, *d* *d'*, and these armatures will consequently be lifted at different times and to different heights by the backward rock of the frame.

It is further observed that each of the armatures of the series *F* and *F'* is within a strong magnetic field before its magnets are placed in the circuit, the first armatures of the series by 130 its position upon the frame, and the others suc-

cessively by the action of the preceding magnets upon the preceding armatures, all rising or falling with the rock-frame, except when they are at rest upon the poles of their respective magnets.

In order to prevent the noise occasioned by the impact of the armatures upon the poles of the magnets, as well as the effects of any residual magnetism communicated to the armatures by their actual contact with the magnets, which would tend to retard the withdrawal of the armatures, stops of some elastic or other proper material may be located near the magnets, upon which the arms *d d'* will strike in their descent, and which will permit the armatures to come into near approach to the poles without the inconvenience of coming in actual contact therewith.

This invention is not limited to the number of armatures employed in the series, as two or any greater number may be employed to advantage, nor to the number, shape, or kind of magnets corresponding to each armature, as a series of single electro-magnets or sets of horseshoe or other magnets connected to constitute substantially a single magnet may be used. Neither is the invention limited, in its more important features, to the shape of the armatures in their relation to the poles of the magnets, nor to any special way of completing or breaking the electric circuit, nor to any special construction of the commutator; but the main and essential features of the invention are the arrangement of series of armatures and series of corresponding magnets operating to bring the armatures successively in contact or in near approach to the poles of the magnets, each armature being brought within the strong magnetic field by the operation of the preceding magnets and armatures of the series.

What is claimed as new is—

1. The combination, substantially as de-

scribed, in an electro-magnetic engine, of a series of stationary magnets and a corresponding series of armatures attached directly to a rock-shaft and swinging on a common center, and arranged at unequal distances from the poles of their magnets and operating to descend toward such poles simultaneously, but to come in contact with or in near approach thereto successively, whereby the full force of each magnet is exerted upon its corresponding armature, and whereby a greater throw or vibration can be given to the lever or link by which the power is transmitted.

2. The combination, in an electro-magnetic engine, of a rock-frame with a series of armatures overhanging the sides of the frame and loosely connected to the rock-shaft by means of arms, substantially as and for the purpose described.

3. In combination with series of magnets and series of corresponding armatures, a rock-frame whose sides adjacent the magnets are provided with series of notches or slots of unequal depth, whereby the armatures are raised one above the other, and are brought in contact with or near approach to their corresponding magnets successively, substantially as described.

4. In an electro-magnetic engine, a series of magnets, each having one of its arms, *b*, inclined toward its corresponding arm, *a*, in combination with a series of armatures swinging on a common center, each of whose faces are in two different planes, one at substantially right angles to the arm *b* and the other at right angles to the arm *a*, substantially as and for the purpose described.
